United States Patent Office

Des. 193,091
Patented June 26, 1962

193,091

HINGE

Horace E. Stocker, Jr., 403 N. Washington, Hinsdale, Ill.

Filed Oct. 10, 1960, Ser. No. 62,432

Term of patent 14 years

(Cl. D10—9)

FIG.1

FIG.3

FIG. 1 is a top plan view of a hinge showing my new design;

FIG. 2 is an end view of the hinge shown in FIG. 1;
FIG. 3 is a top perspective view of the hinge of FIG. 1 showing the parts in separated position.

I claim:

The ornamental design for a hinge, as shown.
